UNITED STATES PATENT OFFICE.

JOSEPH B. HOLDEN, OF UTICA, NEW YORK, ASSIGNOR TO REMINGTON TYPEWRITER COMPANY, OF ILION, NEW YORK, A CORPORATION OF NEW YORK.

TYPEWRITING-MACHINE.

1,397,166.

Specification of Letters Patent.

Patented Nov. 15, 1921.

Application filed March 2, 1920. Serial No. 362,675.

To all whom it may concern:

Be it known that I, JOSEPH B. HOLDEN, citizen of the United States, and resident of Utica, in the county of Oneida and State 5 of New York, have invented certain new and useful Improvements in Typewriting Machines, of which the following is a specification.

My invention relates to typewriting machines and it has for its principal object to provide various improvements in the ribbon feed and reverse mechanism of such machines.

I have shown my invention embodied in 15 a portable typewriter and some of its features are especially designed for use in machines of that class but other of said features are adapted or can readily be adapted to the larger standard typewriters, and 20 other machines that print with an ink ribbon.

My invention includes novel ribbon vibrator mechanism capable of being adjusted for different extents of throw of the vibrator to write in different colors, novel ribbon feed mechanism, and certain details 25 of the ribbon mechanism. The claims of this case are directed to the vibrator mechanism, other features of the ribbon mechanism 30 being claimed in divisional applications.

To the above and other ends my invention consists in certain features of construction and combinations and arrangements of parts 35 all of which will be fully set forth herein and particularly pointed out in the claims.

One embodiment of my invention is illustrated in the accompanying drawings, in which—

40 Figure 1 is a front to rear vertical sectional view partly on the line $x-x$ of Fig. 4 of a portable typewriter having my invention embodied therein, only so much of the machine being shown as is necessary 45 to a full understanding of the invention.

Fig. 2 is a view on an enlarged scale of certain parts of the ribbon feed mechanism, the same being shown in section through the main feed shaft.

50 Fig. 3 is an enlarged perspective view of the parts shown in Fig. 2.

Fig. 4 is a front elevation of the rear part of the machine including a considerable part of my improvements, parts of the machine

being shown in section on the line $y-y$ of 55 Fig. 1.

Figs. 5 and 6 are enlarged sectional views through the middle of one of the ribbon spools and some of the associated parts. In Fig. 6 a certain spool retaining device is 60 shown in normal position and in Fig. 5 said device is shown in released position.

Fig. 7 is a plan view with parts in section on the line $z-z$ of Fig. 1.

Fig. 8 is a fragmentary plan view of a 65 portion of the vibrator movement, the parts being shown by full lines in position for writing by the upper stripe of the ribbon and in broken lines in position for writing by the lower stripe of the ribbon. 70

Fig. 9 is a perspective view of part of the mechanism shown in Fig. 8.

Fig. 10 is a greatly enlarged view, in side elevation and with parts in section and illustrates the mechanism for giving the differential throw of the ribbon vibrator. In this view the parts are shown in the position they occupy at the end of the down stroke of a key, when the mechanism is set to write 75 from the lower or red stripe of the ribbon. 80

The typewriting machine partially shown in the drawings is similar to and as far as my invention is concerned may be identical with the one shown and described in the patent to A. W. Smith, No. 1,342,513, dated 85 June 8, 1920, but as far as most of the features are concerned the details of construction of the machine can be varied and in fact some of the features of my invention are applicable to ink ribbon mechanisms 90 generally.

The main frame of the machine shown in the drawings comprises sheet metal side plates 1 rigidly connected together by several frame members. One of these consists 95 of a front comb plate 2 also of sheet metal and having a series of slots cut both along its upper edge and along its lower edge. Said plate is fastened by means of screws 3 to lugs 4 bent inward from the side plates 100

1. Near to the back of the machine said side plates are connected by a casting designated generally by the numeral 5 and comprising among other things a type bar segment 6 and a sublever segment 7, these 105 segments being integral parts of the casting, which casting at its ends extends to and is rigidly secured to each of the side plates 1.

The machine is more or less inclosed in a casing 8 including a top plate 10 and a base 11, the frame plates 1 being secured to said base by screws 12 and said top plate being secured to the side plates 1 by screws 13, Fig. 4.

The type action of this machine includes top strike type bars 14, Fig. 1, pivoted on a wire 15 supported by the segment 6, which 10 segment is radially slotted to accommodate said type bars. Each of the type bars 14 has on the heel thereof gear teeth meshing with suitable gear teeth on a sublever 16, all of said sublevers working in radial slots of 15 the segment 7 to which they are pivoted on a curved wire 17. Each of the sublevers 16 has a restoring spring 18 and each of said sublevers is connected at its forward end by a link 20 with another sublever 21. The 20 sublevers 21 are mostly levers of the third order each mounted in one of the slots in the upper edge of the comb plate 2 where said sublevers are retained in place by a guard plate 22 constituting part of the casing of 25 the machine. Each of the sublevers 21 is connected by a depending link 23 with a key lever 24 having a printing key 25 on its forward end. The key levers 24 are pivoted at their rear ends in a comb plate 26 having 30 a wire 27 supported thereby to retain the key levers in place. The comb plate 26 is stationary; the supports are not shown in the drawings, but it is preferably supported from the casting 5.

35 The machine has a collapsing feature according to which the type bars 14 can be dropped down from the upstanding position shown in Fig. 1 to a substantially horizontal position. This feature is fully set forth in 40 the patent to A. W. Smith above referred to and it includes a type rest 28 mounted on a segmental support 30 which support can be elevated to the position shown in Fig. 1 or can be moved downward into the depressed 45 central part of the top plate 10, allowing the type bars to drop back into said depressed part of the top plate to make the machine more compact.

The platen 31 is situated in rear of the 50 type bar segment 6 and the type bars are adapted to strike down upon the top of said platen. Each of said type bars carries two types and the platen 31 is made shiftable to print from either type. This platen is 55 mounted on a carriage 32 supported by ball bearing balls 33, said balls running in grooved rails 34 which rails are mounted on brackets 35 constituting part of a case shift frame capable of being shifted toward the 60 rear of the machine from the position shown in order to print the upper case characters.

The case shift frame includes side bars 36, one mounted just inside each of the side plates 1. These plates or bars 36 terminate 65 at their forward ends just in rear of the

comb plate 2 where each of them is pivoted at 37 to an arm 38 rigidly secured to a transverse rock shaft 40 journaled at its ends in the side plates 1. The construction is such that the forward ends of the shift frame are 70 supported by the shaft 40 and said frame can be shifted by rocking said shaft which will insure that the two sides of it move alike. The bars 36 extend rearward nearly to the back of the machine and at their rear 75 ends each of them has a downward extension from which a horizontal bracket 41 is bent inward as shown in Figs. 1, 4 and 7. As best shown in Fig. 4 each of said bars 36 has also an upward extension bent inward 80 to form a bracket or a shelf 42 on which one of the ribbon spools and associated devices are mounted. This shelf is almost entirely hidden in Fig. 1. The two side bars 36 are connected together at their rear ends by 85 a sheet metal cross bar 43, Fig. 4, which at its ends lies on the brackets 41 to which it is secured by screws 44. The brackets 35 to which the carriage rails 34 are directly secured, consist of right and left-hand rear- 90 ward extensions of this bar 43.

The bars 36 are supported at their rear ends in the following manner:—Each of the brackets 41 has bent off therefrom an ear 45, Fig. 1, which at its rear end is pivoted 95 at 46 to an upstanding link 47 which in turn is pivoted at 48 to a rearward extension of one of the side plates 1. Restoring springs 50 for the shift frame are connected with parts of these brackets 35. Somewhat 100 toward the front of the machine each of the side bars 36 has a device 51 secured thereto with which coöperate certain stops (not shown) for limiting the motion of the shift frame.

A universal bar 52 underlying all of the key levers 24 is carried at its ends by levers 53 each pivoted at 54 to one of the bars 36 of the shift frame, so that this universal bar partakes of the shifting motion of said 110 frame. In the vicinity of the pivot 54 the two arms 53 are connected by a cross bar 55 which of course partakes of the oscillating motion of the universal bar when the latter is operated by the key levers. In 115 the present instance the ribbon mechanism is operated from this cross bar 55 as will hereinafter appear. The universal bar is provided with any suitable restoring springs 49.

A shaft 56, Figs. 1, 4 and 7 is located 120 just in front of the platen 31 and said shaft is mounted on pivot screws 57 supported by brackets 58 bent up from the same piece of metal as the cross bar 43 of the shift frame. This shaft at its middle carries the escape- 125 ment feed dogs for controlling the feed of the carriage but to avoid confusion in the drawings neither said feed dogs nor the rack with which they coöperate is shown herein. The shaft 56 at each end thereof carries a 130

forwardly and downwardly inclined arm which is operated by a pin 60 carried by the rear end of the lever arm 53 of the universal bar frame, but these arms have also been 5 omitted from the drawings to avoid confusion. The construction thus far described is or may be substantially the same as that disclosed in the patent to A. W. Smith, hereinbefore referred to.

- 10 The ribbon spools 61 are alike and are of ordinary construction except that the lower flange of each has any suitable number of lugs 62 struck down therefrom out of the metal of the flange for coöperation with 15 the driving mechanism, as will hereinafter appear. The two flanges are connected by a drum 63 on which the ribbon 64 is wound. Each spool is mounted on a vertical post 65 having a flange 66 on which the spool rests, 20 said flange as here shown being enlarged into a nut 67. The post is interiorly threaded and is screwed down onto the screw threaded end 68 of another post 70, Fig. 6, which post is mounted on one of the brackets 25 42 of the shift frame to which it is riveted at 71. Below the screw threaded part 68 the post 70 has a bearing part 72 on which is journaled a beveled gear wheel 73 having a pin 74 projecting upward there- 30 from to such an extent as to coöperate with the lugs 62 of the ribbon spool, so that if the wheel 73 be turned the spool will turn with it. The nut part 67 of the post 65 serves as a retaining nut for the wheel 73. 35 The spools 61 can be readily removed from the machine by merely lifting them off from their posts 65.

I have provided a novel retaining device to prevent accidental displacement of the 40 spools. The post 65 is drilled or bored out from its lower end but the hole does not extend entirely through it but terminates at 45 75. The upper end of the post is diametrically slotted as indicated in the drawings, the slot communicating with the round opening or hole in the post and a retaining device 76 is inserted into the slot and extends on down into the enlarged round hole. The retaining device 76 is made of flat 50 stock and it includes a lug or nose 77 which normally extends out over the top of the ribbon spool 61 as shown in Fig. 6 and prevents said spool from accidental displacement from the post. Said retaining device 55 50 also includes a part 78 shaped to constitute a handle. The retaining device 76 has riveted to its lower end a washer 80 and a spring 81 is coiled about the part 76 and is compressed between said washer and the 60 upper wall 75 of the round hole. The movement of the device 76 under the pressure of the spring 81 is limited by a lug consisting of a pin 82 inserted in said device above the top of the post and normally 65 resting on a lower flat part 83 of said top.

The top of the post has an elevated part or lug 84 and when the device 76 is pushed back from the position shown in Fig. 6 to the position shown in Fig. 5 said pin rides on the elevation 84. In this position of the 70 parts the spool can be lifted off without obstruction. When the retaining device is in its normal position shown in Fig. 6 the shoulder between the two parts 83 and 84 of the top of the post prevents accidental 75 displacement of the retaining device. It will be perceived that this device is effective in preventing any accidental displacement of the spool but that it can be instantly moved out of the way by merely pressing 80 it toward the rear to the Fig. 5 position so that the device is extremely convenient for its purpose.

The ribbon feed mechanism includes a drive shaft 85 having thereon two bevel 85 pinions 86 for driving the bevel gears 73 alternatively. The shaft 85 is journaled in the posts 70 as shown in Fig. 6, and it can be shifted endwise to move one of the pinions 86 out of engagement with its gear 90 73 and the other pinion 86 into engagement with its gear, to reverse the direction of ribbon feed. In the present instance this reverse is effected manually, no automatic reversing means being shown, though it is 95 obvious that such automatic means can be provided if desired. The shaft 85 projects slightly beyond the casing 8 at both ends where it is equipped with milled heads 87 by a manipulation of which the shaft can be 100 shifted to reverse the feed and also the shaft can be turned in order to wind the ribbon manually onto one of the spools.

I have shown an exceedingly simple detent device to retain the shaft in either of 105 its two positions. As shown in Figs. 4 and 7 said shaft has two grooves 88 turned therein and said grooves are connected by a rounded bulging part of the shaft. A wire loop 90 is secured at its ends to one of the 110 brackets 42 by being inserted through holes in said bracket and bent into close contact with the upper and lower surfaces of the bracket as shown in Fig. 4, and the end of said loop is pressed upward by the resilience 115 of the wire into one of the grooves 88. The shaft cannot slide endwise without springing this wire downward over the bulge in the shaft, but the shaft can be pushed endwise by the application of a little force. 120 The extreme simplicity, cheapness and lightness of this retaining device are advantageous and especially so in a portable typewriter.

The shaft 85 is driven step by step by the 125 oscillations of the universal bar 52. A ratchet wheel 91, Figs. 1, 2 and 3, is secured upon the reduced end of a hub 92 which hub is mounted on the shaft 85 to which it is rigidly connected as by a pin 93. The hub 130

device 92 has a flange 94 and on a step of said hub between said flange and the wheel 91 there is journaled an oscillatory device 95, which hangs down at an inclination toward the front of the machine and has a slot 96 therein. A sheet metal pawl 97 is pivoted to the device 95 on a screw 98 and is pressed by a spring 100 into engagement with the teeth of the ratchet wheel 91. This pawl as here shown comprises two ears 101 which are journaled on the pivot screw 98 and a third ear 102 to which the spring 100 is connected at one end, the other end of said spring being connected to a pin 103. The construction is such that if the device 95 be oscillated back and forth the pawl 97 will intermittently turn the ratchet wheel 91 in the direction of the arrows in Figs. 1 and 3, that is to say, toward the rear of the machine at its top. This pawl and ratchet combination is thus permanently mounted on the shaft 85 not far from the middle of the machine. By mounting the operating device 95 on the shaft itself the pawl 97 is caused to engage the ratchet wheel 91 correctly even though the shaft may spring a little. It will be perceived that this pawl and ratchet combination is shifted to the right and left a short distance when the shaft 85 is shifted to reverse the feed.

The actuating device 95 is operated by a pin 104 projecting transversely from an arm 105 which arm as shown in Figs. 1 and 7 is secured by two screws 106 to the cross bar 55 of the universal bar frame. The pin 104 is made long enough so that it remains in the slot 96 in both positions of the shaft 85. In the present instance the arm 105 is bent at a right angle at 107 to bring the sheet metal 40 of which the arm is made into two planes, the upper part of the arm being in a vertical plane and the lower part in a transverse plane so that it can lie flat on the bar 55. Backward rotation of the ratchet wheel 91 may be prevented by any suitable retaining pawl. In the present instance a pawl 108 made of sheet metal has ears 110 bent back therefrom and pivoted on the escapement shaft 56 where it is retained in place lengthwise of said shaft by means of a collar 111, Fig. 7, situated between the two ears 110 and secured to the shaft by a set screw 112. It will be noted that the engaging end of the pawl 108 is made wide enough to allow for the longitudinal shifting of the ratchet wheel 91 with the shaft 85. As shown in Figs. 1 and 7 the frame plate 1 as well as the casing 8 has a notch 113 for the accommodation of the end parts of the shaft 85, this notch opening toward the rear and allowing for the shifting motion of said shaft front and rear in the case shifting operation.

I have shown a pressure plate 114, Figs. 4 and 7, adjacent to each ribbon spool and spring pressed against the ribbon. This

plate can be variously constructed and mounted. As here shown it is pivoted on a pivot screw 115 screwed into the upper end of a post 116 which post rises from a bracket 117 secured as by screws 118 to the bracket 42 of the shift frame. A spring 120 coiled about the post 116 presses the plate 114 against the ribbon. This pressure plate is herein employed for the same purpose as similar devices in other machines. 75

A ribbon vibrator 121 guides the ribbon in its course from one spool to the other. Said vibrator consists of a piece of sheet metal suitably cut out and formed at its rear end to guide the ribbon and lying beneath a flat bracket 122 which serves as support and guide for the vibrator. Said vibrator has tongues or branches 123 projecting from its sides and bent first upward and thence inward to embrace the straight edges of the bracket 122, the construction being such that the vibrator slides freely on said bracket. The bracket 122 slopes somewhat upward and toward the rear and said bracket is secured by screws 124 to the rear face of the type bar segment 6, which constitutes part of the stationary casting 5. A link 125 is at its upper end pivoted to the vibrator on a pin 126 and at its lower forward end it is pivoted on a pin 127 to a lever arm 128 constituting part of a frame which is pivoted at 130 to a bracket 131. Said bracket 131 is part of a fixture 132, which fixture is secured by screws at 133 to the under side of the cross bar 43 of the shift frame. The construction is such that the lever arm 128 and the vibrator are shifted front and back with the shift frame and the platen which is carried thereby. The lever of which the arm 128 is a part, is made of sheet metal and in addition to the arm or branch 128 it includes another arm or branch 134; the two branches 128 and 134 being connected by a yoke 135, Fig. 9. This entire lever frame is made of a single piece of sheet metal, the branches 128 and 134 being bent up into vertical planes from the yoke 135 and both of said arms are pivoted on the ends of the pivot pin 130 which as shown in Fig. 8 is an elongated pin supported by the rolled-up lower edge of the bracket 131. The parts 128 and 134 may be considered as two branches of a lever arm which extends approximately horizontally forward from the pivot 130 and the arm or branch 128 is prolonged upward to its pivotal connection with the link 125 as shown. Said arm 128 has a slot 136 near the forward end of its horizontal part, and the arm 134 is bifurcated at its forward end having two fingers 137 and 138, leaving an open-ended slot 120 between. A wire connector 140 passes through the slot 136 and between the fingers 137 and 138 and is prolonged toward the right as shown in Fig. 8 until it reaches nearly the right-hand side of the machine where it is 125

130

bent to form a rearwardly directed section 141 and it is thence bent toward the right to form another transverse section 142. Said section 142 passes loosely through a hole in 5 a bracket 143 depending from the right-hand bracket 41 of the case shift frame. This whole wire shifts front and rear with the shift frame as do also of course the lever arm 128 and all of its associated devices. 10 Between the arms 128 and 134 the wire 140 is bent toward the rear at an inclination producing an inclined section 144 and thence directly toward the left, producing a transverse section 145 which passes through the 15 slot 136 and which is off-set rearward from the main section 140. The lever arm 128 has a bracket 146 bent off from its lower edge toward the left and thence upward, the up-standing part of said bracket terminating in 20 two tines or fingers between which the section 145 of the wire 140 passes. The construction is such that the wire can be adjusted front and rear by bending or twisting this bracket 146. The lever 128, 134 is operated 25 through the instrumentality of the wire 140 and this adjustment regulates the lever-age of said wire on said lever.

An arm 148 consists of a piece of sheet metal secured by screws 150 to the upper 30 face of the cross bar 55 of the universal bar frame. This arm extends rearwardly from the bar 55 and it has a part 151 thereof bent up into a vertical plane and extending between the two branches 128 and 134 and this 35 vertical part 151 of the lever arm 148 has in it a horizontal slot 152 in which the wire connector 140 lies. When a key is depressed and rocks the universal bar 52 the arm 148 is rocked upward, carrying the wire 140 with it and rocking the pivoted frame 128, 40 134 upward with the result that the upper end of the arm 128 and with it the ribbon vibrator are moved toward the rear of the machine to carry the ribbon over the printing point. In this operation the wire 140 rocks upward at its left-hand end about its 45 point of connection with the bracket 143 as a sort of pivot, the pivotal action however being slight because the wire is rather long in 50 a right and left-hand direction.

In Fig. 8 of the drawing the wire 140 is shown in full lines set for writing on the lower or red stripe of the ribbon; or, in other words, it is set to give its greatest 55 throw to the vibrator; and said wire is shown in broken lines set to give a shorter throw to the vibrator to write by the upper or black stripe of the ribbon. Said wire is slid longitudinally toward the left and toward the right to change from one of these 60 settings to the other. When the wire is in the position shown in full lines in Fig. 8 it is the rear transverse section 145 thereof that passes through the slot 152 in the lever arm 148 and when the wire is shifted to the 65 left for a shorter throw it is the forward transverse section of said wire that passes through said slot. It will be perceived that the pivotal connection between the arm 148 and the vibrator actuating device 128, 134, 70 is farther from the pivotal axis of said arm 148 and nearer to the axis 130 in the former case than in the latter so that said arm 148 is adapted to impart a greater throw to the wire in the first instance than in the second. 75 Any suitable fixed stop can be provided to arrest the vibrator when writing from the lower stripe of the ribbon, but I prefer to make the fixture 132 at its right-hand end with a forwardly projecting stop arm 153 80 which overlies the wire 140 at such an elevation as to arrest said wire at the correct point for writing from the lower or red stripe of the ribbon. This stop can be adjusted up and down by bending it. At its 85 left-hand end the fixture 132 has a stop arm 154 projecting forward therefrom, this arm being bent first downward and thence rearward to make a stop for the free end of the wire 140 but in a lower plane than the stop 153, the stop 154 being adapted to arrest the wire 140 at the correct position for writing from the upper or black stripe of the ribbon. This stop also can be adjusted up and down 90 by bending it. 95

When the wire 140 is set to impart the greatest throw to the vibrator, as shown in full lines in Fig. 8, the end of said wire does not reach to the stop 154 and when the universal bar is operated the wire moves upward beyond said stop, being arrested at that time by the right-hand stop 153.

The wire 140 can be shifted to the left or to the right in order to vary the extent of throw of the ribbon vibrator, by a variety 100 of means. As shown in the drawing, a bell crank 156 is pivoted at 157 to a fixed part of the machine consisting of a bracket 158 projecting inward from the right-hand side plate 1 as shown in Fig. 4. One arm of said 105 bell crank is bent upward at its end to form an ear 160 forked to embrace the rearwardly extending part 141 of the wire 140. The construction is such that when the case shift key is operated the wire 140 moves bodily 110 front and rear with the shift frame, sliding at this time through the notch in the ear 160 without changing the position of said wire in a right and left-hand direction. The bell crank 156 is operated by a 115 wire link 161, Fig. 1, the front end of which is pivoted in the lower end of a lever 162 having its upper end formed into a handle 163. Said lever is pivoted at 164 in a bracket 165 consisting of a piece of sheet 120 metal secured to the side plate 1, the key or finger piece 163 occupying a convenient position at the right-hand side of the keyboard. The bracket 165 has a shelf 166 bent off therefrom and the lever 162 comes up 125 130

through a slot 167 in said shelf, said slot having one wall thereof made with a convex curve as shown in Fig. 7. The lever 162 is put under spring tension toward the left in Fig. 7 so that when moved to one end or the other of said slot 167 the convex wall of the slot acts to retain the lever in its position. Any suitable indices such for example as spots of color 168 can be put on 10 the shelf 166 to guide the operator in adjusting the finger piece 163. In the present instance the rear index 168 might consist of a red spot and the forward one of a black or blue spot.

15 The mode of operation of the differential mechanism between the arm 148 on the oscillator 55 and the lever 128 which operates the vibrator, is worthy of some discussion. In Fig. 10 the parts are shown at the end of a 20 key depression when set for writing red. It will be understood that the extent of oscillation of the arm 148 is the same whether the connection is set for red or black, but the extent of oscillation of the lever 128 is different in the two instances. In Fig. 10 it will 25 be noted that the section 145 of the wire 140, which is embraced by the slot 152 in the arm 148, is pressed upward at *a* by the lower wall of the said slot 152 and that this same 30 section of the wire presses upward at *b* on the upper wall of the slot 136 in the arm 128. The points *a* and *b* where the action of the arm 148 is transmitted to the arm 128 are 35 relatively remote from the pivot 54 of the universal bar and relatively near to the pivot 130 of the arm 128 so that said arm is moved upward a greater distance than it would have been had the forward section of the 40 wire been included in the slot 152. It will be perceived that the section 145 of the wire is pressed upward by the arm 148 at *a*, this section presses the arm 128 upward at *b*, thus 45 rocking the whole frame 128, 134, and the prong 138 of the arm 134 presses upward at *c* on the long section of the wire 140 and presses said long section at *d* against the stop 153. It will thus be seen that in this 50 setting of the parts the rock frame 128, 134 is operated by the arm 128 and is arrested by the arm 134. In the other setting of the 55 mechanism, namely, when the wire 140 is moved to the dotted line position of Fig. 8, then it is the long section of the wire 140 that is in the slot 152 and that is pressed upward by the arm 148. This long section acts on 60 the prong 137 of the arm 134 to rock the frame. The section 145 of the wire moves upward until it is arrested by the stop 154 and the arm 128 moves upward until the 65 lower wall of the slot 136 therein strikes against the wire section 145, thus positively arresting the motion of the frame. It will be seen that when the parts are in the full line position of Fig. 8 the frame 128, 134 is 70 rocked by the left-hand arm 128 thereof.

and is arrested by the right-hand arm 134 thereof and the stop 153 is at the right of said arm 134 and adjacent thereto; whereas in the dotted line position of the parts the frame 128, 134 is operated by its arm 134 75 and is arrested by its arm 128, the stop 154 being located adjacent said left-hand arm 128. In either setting the connector 140 can rock about its longitudinal axis to a sufficient extent to take up all lost motion in the various slots, etc., through which it passes. Though the amount of lost motion has been purposely exaggerated in Fig. 10, the wire is loose; and yet its action is positive and exact, as will be seen in said figure by tracing 80 the application of pressure at the points marked *a*, *b*, *c* and *d*.

The upper wall of the slot 152 in arm 148, 151, is not absolutely essential, or, in other words, the upper finger of the part 151 could 85 be omitted. This finger, or upper wall of the slot is useful, however, and especially as it makes a positive connection between the vibrator and the arm 148 on the return stroke of the parts. If said finger were omitted, a 90 separate returning spring would have to be provided for the vibrator.

It will be noted that this mechanism is of extreme simplicity and cheapness and yet that its action is positive and certain. The 95 stops 153 and 154 can readily be adjusted to arrest the vibrator at the right point in each instance. The leverage of the arm 148 on the connecting wire can very readily be adjusted to give the desired extent of motion 100 by merely twisting the bracket 146 one way or the other. The proper relation of the arm 148 to the rest of the mechanism can be regulated by bending said arm.

The vibratory ribbon guide, in addition to 105 guide prongs or fingers 170 and 171 of ordinary construction, has a spring wire loop 172 soldered or otherwise secured to its under side, the two ends of said loop forming fingers 173 that overlie the lower half 110 of the ribbon between prongs 170 to produce pressure enough to prevent that part of the ribbon from bulging upward, as it has a tendency to do, owing to the angle at which the ribbon passes through the vibrator.

115 The means herein described for feeding the ribbon longitudinally and the latch for preventing the ribbon spool from accidentally coming off of its post, are not claimed herein, but are claimed respectively in two 120 divisional applications filed Jan. 5, 1921, Serial Numbers 435,221 and 435,222, the latter of which has matured into Patent No. 1,379,408, dated May 24, 1921.

125 Various changes can be made in the details of construction and arrangement without departing from my invention.

What I claim as new and desire to secure by Letters Patent, is:—

1. The combination with a ribbon vi- 130

brator and a universal bar, of a lever arm connected with said vibrator, a second lever arm connected with said universal bar, a wire connecting said arms, the wire passing through a slot in one of said lever arms, and an ear on the last mentioned lever arm through which ear said connecting wire passes, said ear being adjustable by bending to adjust the wire slightly lengthwise of said slot to regulate the leverage between said lever arms.

10

bar and lying between said two branches; a wire connector passing through said two branches and operated by said second lever arm and being off-set between said branches and slideable lengthwise to bring one or the other section of the wire into coöperation with the second mentioned lever arm, the construction being such that when the wire is in one of its two positions, said second lever arm acts through said wire on one of said branches to operate the vibrator and

70

75

15 lever arms.

2. The combination with a ribbon vibrator and a universal bar, of a lever arm connected with said vibrator, a second lever arm connected with said universal bar, a wire connecting said arms, the wire connector passing through a slot in one of said lever arms, and an ear on the last mentioned lever arm through which ear said connecting wire passes, said ear being adjustable by bending to adjust the wire slightly lengthwise of said slot to regulate the leverage between said lever arms, and said wire connector being bent into two off-set sections at different distances from the axes of said lever arms and slidably lengthwise to bring one or the other of said sections into use at will and thereby to vary the throw of said vibrator.

when said wire is in its other position said second lever arm acts through the other of said branches to operate the vibrator; and two stops, one in position to arrest said wire in one adjustment of the latter and the other being positioned to arrest said wire in its other adjustment.

6. The combination with a ribbon vibrator and a universal bar, of a lever connected with said vibrator and having one arm thereof made with two branches spaced apart; a second lever arm connected with said universal bar and lying between said two branches; a wire connector passing through said branches and operated by said second lever arm, said connector passing through one of said branches remote from and through the other branch nearer to the

30 3. The combination with a ribbon vibrator, and a universal bar, of a lever connected with said vibrator and having one arm thereof made with two branches spaced apart, a wire connector extending through both of said branches and being off-set between said branches, so that said connector passes through one of said branches farther from the axis of the lever than it does through the other, a lever arm connected 35 with said universal bar and lying between said branches and adapted to operate said connector, and means for effecting a relative adjustment of said connector and the last recited lever arm to cause said lever arm to operate with one section or the other of said connector.

<p

4. The combination with a ribbon vibrator and a universal bar, of two lever arms, the first connected with said vibrator and the second with said universal bar, a wire connecting said arms and bent into two off-set sections and slideable lengthwise to bring one or the other of said sections into use to vary the leverage ratio, and a stop for arresting the shorter motion of the vibrator, said stop being so located that when the connector is adjusted longitudinally in the direction to give a short throw to the vibrator said connector comes into coöperative relation to said stop.

50

55

60

comprising a bell crank 156 to which the wire is connected, a link 161 extending to the front of the machine, and a hand lever 162, 163 for operating said link. 115

8. In a typewriting machine, the combination of a platen shiftable for upper and lower case; a ribbon vibrator; a lever for operating said vibrator, said lever mounted on the shift frame and shiftable with the 120 platen; a universal bar; a lever arm connected with said universal bar and also shiftable with said shift frame; a wire connector between said lever and said lever arm adjustable lengthwise to vary the throw of the 125

5. The combination with a ribbon vibrator and a universal bar, of a lever connected with said vibrator and having one arm thereof made with two branches; a second lever arm connected with said universal ribbon vibrator, said wire connector extending toward the side of the machine and bent to form a section 141 parallel with the direction of the motion of said shift frame and a section 142 parallel with the main 130

body of the wire; a bracket 143 on the shift frame through which said section 142 passes; and a hand operated lever 156 having a slotted ear embracing the section 141 5 so as to move said wire connector lengthwise and to control it in every position of said shift frame.

9. The combination with a ribbon vibrator and a universal bar, of a lever arm connected 10 with said vibrator, a second lever arm connected with said universal bar, and a wire connector between said lever arms, said connector being loosely supported at one end distant from said lever arms and bent to 15 form two off-set sections and slid able lengthwise to bring one or the other of said sections into use, to vary the throw of said vibrator.

10. The combination with a ribbon vi- 20 brator and a universal bar, of a lever arm

connected with said vibrator, a second lever arm connected with said universal bar, a wire connector between said lever arms, said connector being loosely supported at one end distant from said lever arms and bent 25 to form two off-set sections and slid able lengthwise to bring one or the other of said sections into use to vary the throw of said vibrator, and a stop adjacent one of said lever arms and in position to arrest the other 30 end of said connector in one of the adjust ments of the latter.

Signed at Syracuse, in the county of Onondaga, and State of New York, this 24th day of February, A. D. 1920.

JOSEPH B. HOLDEN.

Witnesses:

VERA E. HOUSE,
MERTON C. McLAUGHLIN.
